US0D1019592S

(12) **United States Design Patent** (10) Patent No.: **US D1,019,592 S**
(45) Date of Patent: ** Mar. 26, 2024

(54) **WEARABLE RADIO COMMUNICATION DEVICE**

(71) Applicant: **Roper Solutions, Inc.**, Las Cruces, NM (US)

(72) Inventors: **Maeve Garigan**, San Marcos, TX (US); **Dana De Coster**, Austin, TX (US)

(73) Assignee: **Roper Solutions, Inc.**, Austin, TX (US)

(**) Term: **15 Years**

(21) Appl. No.: **29/788,399**

(22) Filed: **May 14, 2021**

(51) LOC (14) Cl. **14-03**

(52) U.S. Cl.

(57) **CLAIM**

The ornamental design for a wearable radio communication device, as shown and described.

DESCRIPTION

FIG. 1 is a front perspective view of a wearable radio communication device showing our new design;

FIG. 2 is a front elevation view thereof;

FIG. 3 is a rear elevation view thereof;

FIGS. 4 and 5 are left and right side elevation views thereof;

FIG. 6 is a top view thereof;

FIG. 7 is a bottom view thereof; and,

FIG. 8 is a front view of a wearable radio communication device of FIG. 1 in webbing strap environment.

Elements in the figures shown in even broken lines are for illustrative purposes only, showing the environment in which the design is used, and form no part of the claimed design.

1 Claim, 4 Drawing Sheets
